CLAIM

The ornamental design for a display screen or portion thereof with animated graphical user interface, as shown and described.

DESCRIPTION

FIG. 1 is a front view of a first image in a sequence showing a display screen or portion thereof with animated graphical user interface

FIG. 2 is a second image thereof;

FIG. 3 is a third image thereof;

FIG. 4 is a fourth image thereof;

FIG. 5 is a fifth image thereof;

FIG. 6 is a sixth image thereof;

FIG. 7 is a seventh image thereof;

FIG. 8 is an eighth image thereof;

FIG. 9 is a ninth image thereof;

FIG. 10 is a tenth image thereof;

FIG. 11 is an eleventh image thereof;

FIG. 12 is a twelfth image thereof; and,

FIG. 13 is a thirteenth image thereof.

The broken lines showing a display screen or portion thereof and portions of the graphical user interface form no part of the claimed design.

The appearance of the images sequentially transitions between the images shown in FIGS. 1-13. The process or period in which the images transitions to another forms no part of the claimed design.

1 Claim, 13 Drawing Sheets
